(57) **CLAIM**

The ornamental design for a television camera, as shown and described.

DESCRIPTION

FIG. 1 is a front view of a television camera showing my new design;

FIG. 2 is a right side view thereof;

FIG. 3 is a rear view thereof;

FIG. 4 is a left side view thereof;

FIG. 5 is a top plan view thereof; and,

FIG. 6 is a bottom view thereof.

The claim is directed to a perimeter line around a television camera. The planar surfaces within that perimeter are not part of the claimed design.

The portions of the camera in broken lines are shown for illustrative purposes only and form no part of the claimed design.
